Attorneys.

UNITED STATES PATENT OFFICE.

BENJAMIN J. HASTINGS, OF TAUNTON, MASSACHUSETTS.

RAILROAD BRIDGE WARNING.

Application filed April 7, 1923. Serial No. 630,490.

To all whom it may concern:

Be it known that I, BENJAMIN J. HASTINGS, a citizen of the United States, residing at Taunton, county of Bristol, State of Massachusetts, have invented a certain new and useful Improvement in Railroad Bridge Warnings, of which the following is a specification, reference being had thereto in the accompanying drawings.

10 Railroads are required to provide bridge warnings, so-called, suspended over the track to serve as a warning to brakemen on top of freight cars of the near approach to the bridge. These warnings usually consist of a series of telltales in the form of wire hangers pivotally connected to an arm extending crosswise of the track in such manner that they may swing in the direction lengthwise of the track. These wires 20 are usually a foot or so in length, and secured to the lower end of each wire is a rope which hangs down at a sufficient distance, so that if the brakeman is standing or sitting on the top of a freight car the 25 rope will strike him in ample time to enable him to flatten himself on top of the car and thereby avoid striking against the bridge.

In the usual form of construction, one 30 end of the wire is bent around to form an eye which is connected in some suitable manner with the cross arm and the other end of the wire is formed with an eye which is engaged with a loop in the upper end of 35 the rope, so that the rope will swing with relation to the wire, and the wire also has a swinging motion with relation to the crossbar from which it is hung. When the rope is connected with the wire, in the manner 40 above described, which is the usual way, it frequently happens that when the rope is swung up it becomes knotted or twisted, or caught in some way, so that it does not swing back readily into the free 45 downright position that it should occupy. One object of the present invention is to provide an improved hanger and means for connecting the rope with the hanger, whereby both the hanger and the rope have a 50 free swinging movement and yet all danger of the knotting at the connection between the rope and the hanger is avoided.

The sparks from the locomotive frequently fall onto the rope near its lower 55 end and set it afire. There is practically

no danger from the sparks lodging on any part of the rope to do any damage except at the lower end, so that the lower end is set on fire and burns in an upward direction like a slow match on a fuse. One object of the present invention is to provide a protector for the lower end of the rope, whereby danger of burning the same is avoided.

The invention will be fully understood from the following description when taken in connection with the accompanying drawings, and the novel features thereof will be pointed out and clearly defined in the claims at the close of this specification.

In the drawings, Fig. 1 is a view in elevation of a device embodying the invention.

Fig. 2 is an elevation showing a modified form in which the device is shown as being formed with three branches.

Fig. 3 is a view showing a modified form of construction of the eye.

Referring now to the drawings, I provide a metallic hanger or drop member 1 which is tubular, at least at the ends, and is preferably tubular throughout its length. To the upper end of the tube is secured an eye member 2 which is formed with a shank 3 fitted into the end of the tube and secured therein by any suitable means, so that it is rigidly connected therewith. One method of securing the shank 3 within the upper end of the tube is by forming the shank 3 with annular ribs 4 and crimping the tube between the ribs so as to fit snugly. The eye 2 serves for connection with a suitable hanger or holder secured to the cross arm. A rope 5 has its upper end inserted for a short distance into the lower end of the tube and is firmly secured therein by crimping the lower end of the tube so as to form a plurality of points 15 which are pinched into the rope and firmly hold it in connection with the tube. The rope thus hangs from the lower end of the tube and being flexible it is free to swing with relation to the tube, but by reason of there being no loop there is no danger of any entanglement or knotting up as in the old form of construction.

The lower end of the rope is provided with a thimble 7, preferably of metal, which covers the end of the rope and extends a short distance up on the rope and is firmly secured thereto, preferably by pinching in

the upper end of the thimble, and forming a plurality of prongs 8 which engage with the rope in the same manner as the upper end of the rope is connected with the tube 1.

5 In the modified form of construction shown in Figure 2, I have shown the tubular rope holder as being formed with two branches so as to support a plurality of ropes connected with the single hanger. In

10 this form there is shown in addition to the straight downwardly extending tubular member 10, two branch members 11, 12, which branch from the central member 10 at some point intermediate its two ends.

15 These branch members are rigidly connected with the central member and each one of the three members 10, 11, 12 have connected therewith a rope 13 in the manner already described.

20 In the modification shown in Figure 3, the tube 1 is drawn out at its upper end to a smaller diameter and a wire 14 is inserted into the reduced diameter portion 151 of the tube forming a sort of core, and

25 then the small end of the tube with the enclosed wire is bent around to form an eye 16. I wish it to be understood that, while I prefer to make the member 1 out of a tube which is hollow throughout its length, it is

30 not necessary that it be hollow except at its two ends and may be solid between the socket portions, the important feature being that the rod should have a socket at each end, one to receive the eye member

35 at the top and the other to receive the rope at the lower end. In the claims I use the

word tube in the broad sense to include either of the above forms.

What I claim is:

1. A telltale for bridge warning comprising a metallic drop member provided with an eye at the upper end thereof for attachment to a holder, and a rope secured in a socket in the lower end thereof. 40

2. A telltale for bridge warning comprising a tube having an eye at the upper end thereof, and having a rope inserted into the lower end thereof and secured therein by teeth formed in the tube. 45

3. A telltale for bridge warning comprising a tube having means at one end for attaching the same to a support, a drop rope having its upper end secured to the lower end of said tube and a thimble secured to the lower end of said rope by teeth formed 55 on the thimble.

4. A telltale for bridge warning comprising a metallic tube having a rope inserted into the lower end thereof and secured therein by teeth struck from the metal of 60 the tube.

5. A telltale for a bridge warning having a drop rope provided with a spark protector consisting of a thimble of spark proof material which is closed at its lower 65 end and sides and encases the lower end portion of the rope for some distance up from the end.

In testimony whereof I affix my signature.

BENJAMIN J. HASTINGS.
